Primary Examiner — Nathan M Johnston(74) *Attorney, Agent, or Firm* — Justin Lampel(57) **CLAIM**

The ornamental design for a pet waste bag dispenser, as shown and described.

DESCRIPTION

FIG. 1 is a first perspective view of a pet waste bag dispenser showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is a view of the pet waste bag dispenser in an opened state.

The broken lines in the drawings depict portions of the pet waste bag dispenser that form no part of the claimed design.
